LACE ATTACHMENT FOR FLAT KNITTING MACHINES

Fritz Lambach, Fairview, N. J.

Application August 30, 1939, Serial No. 292,549

26 Claims. (Cl. 66—96)

The present invention relates to a lace attachment for flat knitting machines, and primarily aims to provide an attachment of simplified construction capable of being readily installed on commonly used flat knitting machines and operated at relatively high speed for producing lace effects in flat knitted fabrics.

Heretofore, it has been customary to equip knitting machines with plain picot mechanisms and to associate therewith so-called lace attachments intended to control the picot mechanisms for forming lace designs in the fabrics knitted on said machines. Such known arrangements, however, present complications and result in considerable loss of time and production due to the fact that the setting of the machine provided with known lace attachments requires a number of manual operations, such as the manual setting of the attachment into operative position, the manual setting of the narrowing motion mechanism and of the carrier rod control mechanism to prevent the operation thereof during the function of the lace attachment.

It is, therefore, one of the most important objects of the invention to provide a flat knitting machine having loop transfer devices, such as a picot bar or lace comb mechanisms, with means operable to set the machine quickly and automatically for the formation of lace designs in the fabric by said picot bar or lace comb mechanisms, thereby eliminating those slow manual operations which have heretofore been necessary.

Other important objects and advantages of the invention will be in part obvious and in part pointed out hereinafter.

In order that the invention and its mode of operation may be readily understood by those skilled in the art, I have, in the accompanying drawings and in the detailed description based thereupon, set out a possible embodiment of the invention.

In these drawings:

Figure 1 is a front elevation of a portion of a knitting machine having my improved lace attachment installed thereon.

Figure 2 is a section taken on line 2—2 of Figure 1.

Figure 3 is an enlarged detail of a portion of the mechanism illustrated in Figure 2.

Figure 4 is a front elevation of my improved lace attachment mechanism.

Figure 5 is a top plan of the same.

Figure 6 is a section on a reduced scale taken on line 6—6 of Figure 4.

Figure 7 is a section taken on line 7—7 of Figure 4, but on a reduced scale.

Figure 8 is a section taken on line 8—8 of Figure 4, but on a reduced scale.

Figure 9 is a section taken on line 9—9 of Figure 5, but with parts removed.

Figure 10 is a view similar to Figure 3, showing the association of the picot rod and lace rod with the lace attachment.

Figure 11 is a plan view of a portion of the same.

Having more particular reference to the drawings, wherein like characters of reference will designate corresponding parts throughout, it is pointed out that I have shown only those parts of a full-fashioned knitting machine which are essential to a clear understanding of the present invention, the basic construction and operation of the machine itself being that of the usual standard machine well known in the art.

Machine frame

In the drawings, the usual machine frame is represented at 1, and includes the upright frames 2, front beam 3, the table 4, and the center bed 5. The upright frames 2 are provided with the usual aligned bearings to support the longitudinally shiftable main cam shaft 6, the rotatable hand wheel shaft 7, the rockable back catch shaft 8, and the rockable back narrowing shaft 9.

Knitting mechanism

Mounted in the usual manner about the center bed 5 are the knitting sections, one of which is represented at 10 in Figures 1 and 2 of the drawings. Each knitting section includes the needle bar 11 with which the usual yarn carriers (not shown) carried by the carrier bars 12, the sinkers 13 operated through jacks 14, and the dividers 15 actuated through the catch bar 16 cooperate to form the loops of the fabric being knitted on the machine.

Carrier bar control mechanism

Arranged upon the machine is the yarn carrier bar motion control mechanism, designated in its entirety for convenience herein by the reference character 17, and functioning in the usual manner to vary the stroke of the carrier bars 12 in their yarn laying movements. The yarn carrier bar motion control mechanism includes a pair of carrier nuts 18 in engagement with a rotatable reversely threaded spindle 19 whereby said carrier nuts may be moved towards and away from each other, depending upon the rotating direction of said spindle.

Whereas the carrier nut spindle 19 may be rotated through actuation of the usual manually operated means 20, it is rotated automatically during the function of the knitting machine by means of a gear 21 keyed, or otherwise secured, to said spindle 19, and enmeshed with a gear 22 secured to a shaft 23 rotatably mounted in bearings 24 suitably fixed to the center bed 5. The shaft 23 is rotated by means of a ratcheting mechanism 25 comprising a ratchet wheel 26 fixed on said shaft and acted upon by a pawl 27 carried by a connection rod 28 articulated as at 29 to an oscillating lever 30 pivotally supported on one of the upright frames 2, as shown at 31, and provided with a roller 32 adapted for engagement in the usual manner with push cams 33 and 34, a spring 35 acting on the lever 30 to urge the same into its normal position.

Narrowing mechanism

Also arranged upon the machine is the narrowing mechanism operating in the usual manner to transfer loops on the needle bar 11 for fashioning the fabric. The narrowing mechanism includes sets of narrowing combs 37 adapted for cooperation with the needle bar 11 to effect the transfer of loops, and carried by sets of narrowing rods 38 slidably suspended over the knitting sections by means of brackets 39 relatively spaced along a shaft 40 extending longitudinally of the machine and mounted in vertically disposed arms 41 clamped onto the back narrowing shaft 9 for oscillating movement therewith.

Narrowing rod motion mechanism

The narrowing mechanism is controlled by means of a narrowing motion mechanism designated in its entirety by the reference character 36, and including a narrowing spindle 43 rotatably carried in longitudinally superposed paralleling relation to the shaft 40 by means of bearing brackets 42 positioned at suitable intervals along the length of said shaft. The narrowing spindle 43 is formed with the usual reversely threaded portions 44 in engagement with the usual narrowing nuts, one of which is shown at 45, it being understood that the required number of reversely threaded portions and narrowing nuts are provided to impart the necessary narrowing movement to each of the narrowing rods 38 which, for that purpose, have stops, such as represented at 46, to engage said nuts in the usual manner.

The spindle 43, while capable of manual rotation by actuation of the hand crank 47 and gearing 48, is automatically rotated during operation of the knitting machine by means of a pawl and ratchet mechanism 50 comprising a ratchet wheel 51 acted upon by a pawl 52 receiving its motion from a rod 53 connected, as shown at 54, to one end of a rocking lever 55, having its other end affixed onto the back catch bar shaft 8 which carries an arm 56 provided with a roller 57 disposed for riding engagement with either a narrowing cam 58 or idling cam 59 on the main cam shaft 6, depending upon the shifted position of said main cam shaft.

Proper setting of the narrowing nuts, and accidental rotation of the narrowing spindle, are prevented by means of the usual locking mechanism 60 consisting of an index wheel 61 and cooperating spring pressed plunger 62.

Picot rod and lace rod mechanism

The knitting machine, in accordance with the

present invention as herein shown, is equipped with a picot rod 64 mounted for longitudinal sliding and transversal rotating movements in bearings 65 on the brackets 39. Disposed for registration with each knitting section, and fixed to the picot rod 64 by means of the arms 66, is a picot bar 67 which may be moved in and out of cooperative position with respect to the needle bar 11 by the transversal rotating movement of the picot rod, and which may be moved longitudinally of said needle bar for the transfer of loops through the longitudinal sliding movement of said picot rod for the formation of picot lace designs in the fabric, in the manner hereinafter specified.

The knitting machine, also in accordance with the present invention as herein shown, may be provided with a lace rod 68 mounted for longitudinal sliding and transversal rotating movements in bearings 69 in the brackets 39 and fixedly carrying lace combs, such as the comb indicated at 70 in Figure 10, for the transfer of loops through the longitudinal sliding movement of said lace rod to form clock designs in the fabric, in the manner to be set forth hereinafter.

The picot rod 64 and lace rod 68 may be rotated to operative or inoperative positions by means of handles suitably attached thereto, for instance, as that shown at 71 in the drawings.

Timely dipping motion of the entire narrowing mechanism, including the picot and lace mechanisms just described, is had through link arrangement 72 provided with roller 73 adapted for riding engagement with either a dipping cam 74 or an idling cam 75 on the main cam shaft 6, depending upon the shifted position of said cam shaft. The picot rod 64 and lace rod 68 are given their respective longitudinal movements for the loop transference to form the desired lace designs in the fabric being knitted by the function of a so-called lace attachment, designated in its entirety by the reference character 80, which will now be described.

Lace attachment

Fixedly attached to the table 4 of the machine frame 1 is a frame casting 81 consisting of a base 82 and sides 83 and 84. Depending from the front portion of the base 82 and suitably secured thereto, for instance, as indicated at 85, is a bearing bracket 86 which preferably is steadied by means of a supporting arm 87 having one end bolted, or otherwise fastened, to said bracket 86, and its other end affixed to the front beam 3 of the machine frame 1, as indicated at 88 and 89 respectively.

Journalled in the bearing bracket 86 is a rotatable stub shaft 90 fixedly carrying a lever 91 provided with a roller 92 disposed to contact with and ride either upon an active lace cam 93 or a neutral lace cam 94. Proper riding engagement of the roller 92 with either cam 93 or cam 94 is assured by means of springs 95, each having one end attached to the lever 91, as shown at 96, and the other end attached to the bracket supporting arm 87, as shown at 97.

Also fixedly carried by the stub shaft 90 is a second lever 98 terminating with an arcuate rack portion 99 in engagement with a gear 100 keyed, or otherwise locked, onto a shaft 101 supported at one end portion by a bearing 102 formed in one side 83 of the frame casting 81, and at the other end portion by a bearing 103 formed with a support member 104 extending from the base 82 of the casting 81.

Rigidly mounted upon the shaft 101 are three groups of cams, one group consisting of a push cam 105, the second group consisting of a set of shift cams respectively designated at 106a, 107a, 108a, 106b, 107b, and 108b, and the third group consisting of an unloading cam 109.

Associated with the push cam 105 is a roller 110 carried by one arm 111 of a bell crank lever 112 fixed onto a shaft 113 supported by the sides 83 and 84 of the frame casting 81 in parallel spaced relation to the cam carrying shaft 101. The roller 110 is constantly urged into riding engagement with the push cam 105 by means of a spring 114 having one end connected to said arm 111 of the bell crank lever 112, as shown at 115, and the other end connected to the base 82 of the casting 81, as shown at 116. The other arm of the bell crank lever 112 forms a handle 111a for the purpose to be set forth hereinafter.

Upon the roller carrying end of the bell crank lever 112 is also mounted a pawl 117 disposed for action on, and adapted to be normally urged, by means of a spring 118 between said pawl 117 and bell crank lever 112, in engagement with a ratchet wheel 119 rotatably engaging the shaft 113 and having one of its faces provided with two concentrically disposed rows 120 and 121 of buttons, the buttons in each row being of relatively different lengths for the purpose to be hereinafter specified.

Disposed to abut the buttons in one row 120 is a longitudinal shiftable shaft 122 provided, for that purpose, with a tapering end 123. The shaft 122 is supported in a bearing 124 formed with the support 104 and a bearing 125 formed with the side 83 of the frame casting 81 so that said shaft 122 may be shifted longitudinally with respect to the shaft 113. Arranged for longitudinal sliding movements with the shaft 122, but mounted for transversal rocking movements relative thereto, is a forked lever 126 having a pair of spaced arms 127 and 128 relatively projecting in opposite directions so that rollers 129 and 130 carried by the free end of each respective arm 127 and 128 may extend on the opposed sides of said second cam group on the shaft 101 for cooperating with shifting cams 106a, 107a, 108a, 106b, 107b, and 108b of said second group for imparting to the forked lever 126 its rocking motion.

It is to be noted that the roller 129 is disposed to cooperate with cams 106a, 107a, and 108a, whereas the roller 130 is disposed to cooperate with cams 106b, 107b, and 108b, that is, depending upon the shifted position of the shaft 122, the roller 129 will engage cam 106a, whereas roller 130 will engage cam 106b; or the roller 129 will engage cam 107a, whereas roller 130 will engage cam 107b; or roller 129 will engage cam 108a, whereas roller 130 will engage cam 108b. It is also to be noted that the various cams are so shaped that one cam always follows the other, so that the rocking movement of the forked lever 126 is constant and positive, without the use of springs. Because of this arrangement, it will be appreciated that said forked lever may easily be shifted with the shaft, since no spring pressure between the rollers 129 and 130 and the associated cams has to be overcome.

The forked lever 126 engages, preferably by means of slots 131, a relatively short rod 132 received in an elongated slot 133 cut longitudinally through one end portion 134 of a wedge 135 carrying a knurled nut 136 in screw-threaded engagement with said end 134, whereby said rod 132 may be adjusted in the elongated slot with re-

spect to the wedge 135, thereby constituting an adjustable connection between said lever 126 and wedge 135. Because of the connection between the forked lever 126 and the wedge 135, it will be understood that the rocking movements of the former will impart sliding movements to the latter, and that therefore the action of the shifting cams will control the position of the wedge 135 at various levels.

10 The intermediate portion 137 of the wedge 135 passes for transversal sliding movement through a longitudinally hollowed portion 138 in one end of an elongated member 139 supported for reciprocation by means of a bearing 140 on the support 104, and a bearing 141 on one side 83 of the frame casting 81. The other end portion of said member 139 projects outwardly of the casting side 83, as shown at 139a, and rigidly carries a face plate 141a with which the picot rod 64 and lace rod 68 are adapted to be engaged, as will more clearly be set forth hereinafter. Said intermediate portion 137 of the wedge 135 is formed with a stepped surface 142 disposed to contact one end 143 of a pin 144 slidably received within said hollowed portion 138 of the member 139, the free end 145 of said pin 144 projecting outwardly of the member 139 and suitably shaped for abutting engagement with the row 121 of buttons on the ratchet wheel 119.

20 30 It will be understood that the stepped surface 142 of the wedge 135 acts to cause the pin 144 to move more or less in or out of the member 139, thereby, in actuality, acting to lengthen or shorten the length of said member 139 which, in turn, causes the shifting of the picot rod 64 or lace rod 68 in relation to the needle bar 11 by reason of the engagement of said picot rod or lace rod with the face plate 141a carried by said member.

40 45 50 55 60 In the embodiment shown in the drawings, the stepped surface of the wedge 135 is composed of four steps, one step A acting to shift and hold the picot bar 67 or lace combs 70 in neutral or starting position with respect to the needle bar 11; the second step B acting to shift and hold the picot bar or lace combs in a position two needles to the left from the original or starting position, the third step C acting to shift and hold the picot bar or lace combs in a position one needle to the right from the starting position; and the fourth step D acting to shift and hold the picot bar or lace combs in a position two needles to the right from the starting position. Of course, it is to be understood that the number of steps and their relation may be varied at will, to cause the shifting and holding of the picot bar or lace combs to other and different positions in either right or left directions with respect to the needle bar to produce various desired lace designs in the fabric being knitted.

65 70 75 80 85 90 Positive frictional engagement between the end 143 of the pin 144 and the stepped surface 142 of the wedge 135 is assured by means of a spring 146 suitably connected to said pin 144 and member 139, as represented at 147 and 148, whereas positive abutting engagement of the end 145 of the pin 144 with the row 121 of buttons, is assured by means of a spring 149 connected to a suitable portion of the supporting bearing 140 and member 139, as represented at 150 and 151 (Figure 5) and positive abutting engagement of the end 123 of the shaft 122 is assured by means of a spring 152 connected to said shaft 122 and base 82, as indicated at 153 and 154 (Figure 9).

The pin 144 is guided in its sliding movement

by means of a guide plate 155 affixed to the support bearing 140, as shown at 156; the wedge 135 is guided in its sliding movement by means of a guide cap 157 affixed to member 139, as shown at 158, to enclose the free end of said wedge; and the rod 122 is guided in its movement with said wedge by means of a guide plate 159 affixed to the support 104, as shown at 160.

In order to prevent the accidental rotation of the shaft 113 with the ratchet wheel 119 thereon, an index wheel 161 is secured to said shaft adjacent the outer face of said ratchet wheel, and is adapted to be engaged by a spring pressed retractable plunger 162 fixed onto the side 84 of the frame casting 81. Also, in order to prevent the ratchet wheel 119 from over-running because of its own momentum, there may be provided a suitable frictional brake 163 arranged to bear upon the face of said ratchet wheel.

Associated for riding engagement with the unloading cam 109 on the shaft 101 is a roller 164 carried by a rocking lever 165 movably mounted upon the shaft 113 and normally pulled in a direction to cause said roller 164 to engage the cam 109 by means of a spring 166 suitably attached to the lever 165 and the base 82 of the frame casting 81, as indicated at 167 and 168 (Figure 8).

The lever 165 is formed with a pair of camming elements 170 and 171, one camming element 170 being adapted to engage a roller 172 carried by the sliding member 139, and the other camming element 171 being adapted to engage a roller 173 carried by the sliding shaft 122. Because of this arrangement, it will be understood that, upon movement of the cam 109 in the direction indicated by the arrow X (Figure 8), the lever 165 will be rocked, accordingly moving the cam elements 170 and 171 in the direction indicated by arrows Y and Z respectively, thereby displacing member 139 and shaft 122 so that their respective ends 145 and 123 will disengage the rows 121 and 128 of buttons on the ratchet wheel 119.

As represented in the drawings, the gearings, shafts, and cams confined within the frame casting 81 may be enclosed by means of a covering shield 174 for protection and safety purposes.

As is customary in the art, whenever the knitting machine is to knit plain fabric, the lace attachment 89 hereinbefore described is to be rendered inoperative so that the carrier bar control mechanism 17 and the narrowing rod motion mechanism 36 may operate freely to provide their intended functions, and whenever said lace attachment is to function, said carrier bar control mechanism and narrowing rod motion mechanism are to be rendered inoperative so as not to interfere with the proper actuation of the picot or lace mechanism.

In accordance with the present invention, the change in the knitting machine is accomplished automatically by the mere lowering of the picot bar 67. For that purpose, the picot rod 64 is provided with a cam 175 disposed for engagement with a finger 176 formed with a plate 177 positioned adjacent the ratchet 59 of the narrowing rod motion mechanism 36 and mounted for rectilinear sliding movement on supporting shafts 40 and 43. A portion of the plate 177 is preferably rounded out, as shown at 178, to lay concentrically with respect to the ratchet wheel 51. In this manner, as more clearly shown in Figure 3, when the picot rod 64 is rotated to place the picot bar 67 in active position, the high point of the cam 175 will raise the plate 177 and cause the rounded portion 176 thereof to lift the pawl

52 out of engagement with the ratchet wheel 51, thereby rendering the narrowing mechanism 36 inactive.

However, when, as more clearly shown in Figure 10, the picot rod 64 is rotated to place the picot bar 67 in inactive position, the high point of the cam 175 leaves the finger 176, allowing the plate 177 to fall by gravity accordingly freeing the pawl 52 for its engagement with the ratchet wheel 51, thereby rendering the narrowing rod motion mechanism active.

The picot rod 64 is also provided with a second cam 180 disposed for engagement with one end 181 of a lever 182 supported for oscillating movement in a bracket 184 attached to the table 4, the lever 182 being constantly urged in engagement with the cam 180 by the action of a spring 185 attached to said lever 182 and bracket 184, as indicated at 186 and 187. The other end 188 of the lever 182 is connected by means of a link 189 to an arm 190 formed in a circular plate 191 positioned adjacent the ratchet 25 of the carrier bar control mechanism 17 and mounted for rocking motion on the shaft 23.

As illustrated in Figure 3, the peripheral edge of the plate 191 which extends slightly beyond the teeth of the ratchet wheel 26 is adapted to engage and remove the pawl 27 from the latter, thereby rendering the carrier bar control mechanism 17 inactive. Said peripheral edge of the plate 191, however, is formed with a cut-out portion 192 intended to allow the pawl 27 to engage the ratchet wheel 26 when the picot rod 64 is rotated to place the picot bar 67 in inactive position, which brings the high point of the cam 180 in engagement with the lever 182 to cause the plate 191 to move in the direction of the arrow W, accordingly bringing said cut-out portion 192 in registration with the pawl 27.

The picot rod 64, however, is provided with a third cam 194 disposed for engagement with an arm 195 rigid with a sleeve 196 rotatably mounted on a stud 197 projecting outwardly from the side 83 of the frame casting 81. The sleeve 196 is formed with a second arm 198 connected by means of a link 199 to a lever 200 positioned on the outside of said casting side 83 and pivoted at its intermediate portion on the extremity of the shaft 101. The other end of the lever 200 carries a stop 201 passing through an arcuate slot 202 cut into said casting side 83 to project at a point in alignment with the rack 99 with which the gear 100, also carried by the shaft 101, is in engagement.

The stop extension carrying extremity of the lever 200 is engaged by a spring 203 attached to the casting side 83, as indicated at 204, and acting on said lever 200 to normally urge the stop extension 201 thereof towards the rack 99. By reason of this arrangement, and as more clearly shown in Figure 3, it will be understood that when the picot rod 64 is rotated to place the picot bar 67 in operative position, the high point of the cam 194 bears upon the arm 195 to act through arm 198 and link 199 on the lever 200 for holding the stop extension 201 away from the rack 99 against the normal action of the spring 203, thus permitting the free movement of the arm 98 through the lever 91 and the cam 93 on the main cam shaft 6.

However, when the picot rod 64 is rotated to place the picot bar 67 in inoperative position, the high point of the cam 194 leaves the arm 195 which then moves in the direction indicated by the arrow M, accordingly allowing the spring

203 to pull the stop extension 201 towards the rack 99 which, by that time, has moved to a position opposite to that shown in Figure 3. The stop extension 201 may then engage the rack 99 and prevent further movement thereof, thus rendering the entire lace attachment 80 inoperative.

As shown in the drawings, the cam 194 on the picot rod 64 is provided with an adjustable stop 205 adapted to contact the face plate 141a carried by the reciprocating member 139 when the picot rod 64 is rotated to place the picot bar 67 in active position so that the reciprocations of said member 139 are transmitted to the picot bar 67.

In Figures 10 and 11, there has been shown a possible way of operating the lace rod 68 by means of the lace attachment 80.

Arranged upon the lace rod 68 is a cam 206 disposed for engagement with an extension piece 207 rigid with the lever 198 of the lace attachment control assembly, hereinbefore described. Thus when said lace rod 68 is rotated to bring the lace combs 70 into active position, the high point of the cam 206 acts through the extension piece 207 on the lever 198 in the same manner as the cam 194 of the picot rod 64 to free the lace attachment for operation.

The cam 206 likewise is provided with an adjustable stop 208 adapted to contact an extension 209 rigid with a face plate 141a so that said lace rod, together with its lace combs, may follow the reciprocating movements of the member 139. The lace rod 68 may also be provided with similar cams disposed for cooperation with suitable extensions (not shown) rigid with lever 182 and finger 176, so that the movement of said lace rod will govern automatically the carrier control mechanism and the narrowing motion mechanism in the same manner as hereinbefore described.

However, since the lace combs usually are so located, and of such a size, that they do not interfere with the operation of the narrowing combs 73, narrowing may be performed in conjunction with the use of the lace combs. In this event, additional cams on the lace rod 68 and extensions on the lever 182 and finger 176 may be dispensed with so that movement of the lace rod to place the lace combs in active position will not disrupt the action of the carrier rod control mechanism and narrowing mechanism.

Operation

During the normal operation of the knitting machine, that is, during the knitting of plain fabric, the main cam shaft 6 is shifted to its knitting position so that the roller 92 rides on the idling cam 94, which causes the rack carrying lever 98 to assume its position opposite to that shown in the drawings. Since, during plain knitting, the picot bar 67 and the lace combs 70 are raised, the cam 194 on the picot rod 64 and the cam 206 on the lace rod 68 are so positioned that the high point of each of said cams is moved away from the lever 195 and its extension 201, thus permitting the lever 200 to move and bring the stop extension 201 thereof in engagement with the rack 99, accordingly locking said rack and its lever 98 against movement.

In this manner, when, in the process of plain knitting, the main cam shaft 6 is shifted to its narrowing position for the purpose of fashioning the fabric, the lace attachment 80 remains inactive, although the active cam 93 is brought into

alignment with the roller 95. It will be understood that the shifting of the main cam shaft 6 to its narrowing position also brings the active cams 33, 58, and 75 into alignment with the rollers 32, 57, and 73 respectively, imparting movement to the carrier rod control mechanism, the narrowing rod motion mechanism, and the dipping mechanism. In this connection, it will be noted that the carrier rod control mechanism 17 and the narrowing rod mechanism 36 are free to operate because the picot rod 64 with the cams 180 and 175 are turned so that the high point of each of said cams is away from the lever 182 and finger 176.

15 It will be understood, particularly upon reference to Figure 8, that while the lever 98 is moved for engagement by the locking extension 201, the unloading cam 109 is moved in the direction of arrow X, causing the cam elements 170 and 171 to displace and hold the member 139 and shaft 122 so that their respective ends 145 and 123 are maintained away from the rows 121 and 120 of buttons on the ratchet wheel 119. Thus it is possible to rotate said ratchet wheel by means 20 of the handle 111a for setting the attachment into proper desired starting position.

When it is desired to utilize the picot bar 67 for the formation of picot lace designs in the fabric, the picot rod 64 is rotated by means of 30 the handle connected to bring said picot bar in position for cooperation with the needle bar 11. As already stated, the rotation of the picot bar automatically locks the lace attachment 80 and 35 interrupts the function of the carrier rod control mechanism 17 and of the narrowing motion mechanism 36. With the pivot bar 67 in operative position, the knitting machine functions in the usual manner to knit successive courses and to cause the picot bar to pick the loops off the 40 needle bar 11 for the purpose of transferring said loops when a picot course is to be formed.

For the formation of such a picot course, the main cam shaft 6 is shifted to its narrowing position through the normal operation of the machine 45 following the knitting of a course. The shifting of the main cam shaft brings the active cam 93 in position to act on roller 92 so that, during the subsequent rotation of said main cam shaft, the lever 98 moves, causing the rack 99 to rotate the shaft 101 through the gear 100. The rotation of the shaft 101, it will be understood, returns the cam 109 to the position shown in Figure 8 and thus allows the lever 165 to rock, which moves the cam elements 170 and 171 to free the member 50 139 and shaft 122 so that, as more clearly shown in Figure 9, their respective ends 145 and 123 abut the associated rows 121 and 120 of buttons on the ratchet wheel 119. In this manner, the picot rod 64, because of its engagement with the face plate 141 carried by said member 139, is set 55 in that position which determines the location of the picot bar 67 in relation to the needle bar 11 for the picking of the loops therefrom. Thereupon, the dipping cam 14 acts on the roller 73 and causes the picot bar to pick the loops off the needle bar. At that time, the cam 93 again acts on the roller 92 and thus rocks the rack carrying lever 98 to oscillate the shaft 101, accordingly moving the cam 105 to actuate the pawl 117 and therefore advance the ratchet wheel 119 one step, thereby setting the picot rod 64 in that position which determines the location of the picot bar 67 in relation to the needle bar 11 for the shifting of the loops.

After the shifting has taken place, the dipping

cam 74 acts on the roller 73 and causes the picot bar to re-deposit the shifted loops onto the needle bar. Following the completion of the loop transfer, the cam 93 moves the roller 92 in line with the edge of the idling cam 94, whereupon the main cam shaft 6 is shifted to its knitting position so that the machine may continue to knit while the lace attachment remains inoperative until the main cam shaft is again shifted to its narrowing position for the formation of another picot course in the same manner above set forth.

It will be understood that the operations of the machine and lace attachment are the same when it is desired to utilize the lace combs instead of the picot bar, and that whether the lace combs or the picot bar are used, the knitting machine and lace attachment are set automatically for the knitting of lace fabric by the mere placing of said combs or bar into operative position.

It is pointed out that constant engagement of the picot rod 64 and lace rod 68 with the face plate 141 when in operative relation thereto, may be assured by providing usual draw springs (not shown) connected to suitable points on said rods and machine frame.

It is, of course, to be understood that the embodiment of the invention herein shown and described is capable of several modifications and, therefore, any modifications coming within the scope of the subjoined claims are to be considered within the spirit of the invention.

What I claim is:

1. In a flat knitting machine having a main cam shaft and a loop transfer device movable in and out of operating position: a lace attachment comprising a rotatable pattern wheel; a lace cam on said cam shaft; means arranged between the cam shaft and pattern wheel and adapted to be actuated by said cam for imparting intermittent rotation to said pattern wheel; adjustable means controlled by said pattern wheel and adapted to act on said loop transfer device to operate the same; adjusting means also controlled by said pattern wheel to adjust said adjustable means for varying its action on said transfer device; and means associated with the loop transfer device and operable with its movement out of operating position for locking said rotation imparting means against actuation by said cam.

2. In a flat knitting machine having a main cam shaft and a loop transfer device movable in and out of operating position: a lace attachment comprising a rotatable pattern wheel including two sets of pattern elements; a lace cam on said cam shaft; means arranged between said cam and pattern wheel and adapted to be actuated by the cam for imparting intermittent rotation to the pattern wheel; adjustable means controlled by one set of pattern elements on said pattern wheel and adapted to act on the loop transfer device to operate the same; adjusting means controlled by the other set of pattern elements on the pattern wheel to adjust said adjustable means for varying its action on the transfer device; and means associated with the loop transfer device and operable with its movement out of operating position for locking said rotation imparting means against actuation by said cam.

3. In a flat knitting machine having a carrier bar control mechanism, a narrowing rod motion mechanism, and a lace mechanism including loop transfer means movable to and from operating position; means under control of said loop transfer means and operable upon moving the latter

to operating position for setting said lace mechanism for actuation and simultaneously preventing actuation of said carrier bar control mechanism and narrowing rod motion mechanism.

4. In a flat knitting machine having a carrier bar control mechanism, a narrowing rod motion mechanism, and a lace mechanism including a loop transfer means movable to and from operating position: a device normally permitting, but movable to prevent, actuation of said carrier bar control mechanism; a device normally permitting, but movable to prevent, actuation of said narrowing rod motion mechanism; a device normally preventing, but movable to permit, actuation of said lace mechanism; and means under control of said loop transfer means and operable upon movement of the latter to operative position for simultaneously moving all of said devices.

5. In a flat knitting machine having a carrier bar control mechanism and a picot lace mechanism including a picot rod and a picot bar thereon, said picot rod being movable to place the picot bar in and out of operating position: a device normally permitting, but movable to prevent, actuation of said carrier bar control mechanism; a device normally permitting, but movable to prevent, actuation of said narrowing rod motion mechanism; a device normally preventing, but movable to permit, actuation of said picot lace mechanism; and cams carried by said picot bar and disposed to act on all of said devices for simultaneously moving the same with movement of the picot rod to place the picot bar in operating position.

6. A flat knitting machine comprising a carrier bar control mechanism; a narrowing rod motion mechanism; a lace attachment including a loop transfer device movable to and from operating position; and means controlled by said transfer device and operable, upon moving the latter to operating position, for automatically and simultaneously setting the lace attachment for actuation and preventing the action of the carrier bar control mechanism and the narrowing rod motion mechanism.

7. A flat knitting machine comprising a carrier bar control mechanism; a narrowing rod motion mechanism; ratchet devices for operating said mechanisms; a lace attachment including a loop transfer device movable to and from operating position; and means controlled by said transfer device and operable, upon moving the latter to operating position, for automatically and simultaneously setting the lace attachment for actuation and preventing the action of the carrier bar control mechanism and the narrowing rod motion mechanism, said means consisting of cams carried by the loop transfer device and of elements controlled by said cams to govern the function of said ratchet devices.

8. A machine for knitting flat fabric comprising a knitting mechanism including a needle bar, and carrier bars operable to feed yarn to the needle bar for the knitting of courses of loops forming the fabric: a carrier bar control mechanism including carrier nuts and means to actuate the same; a narrowing mechanism including narrowing rods and narrowing combs operable to transfer certain loops in certain of said courses for fashioning the fabric; a narrowing rod motion mechanism including narrowing nuts and means to actuate the same; a lace attachment including a loop transfer device movable to operating position in relation to said needle bar to transfer thereon all the loops in certain of

said courses for forming lace designs in the fabric; and means controlled by said transfer device and operable, upon movement of the latter to operating position, for automatically setting the lace attachment for actuation and preventing the action of the carrier bar control mechanism and the narrowing rod motion mechanism.

9. A machine for knitting flat fabric comprising a knitting mechanism including a needle bar, and carrier bars operable to feed yarn to the needle bar for the knitting of courses of loops forming the fabric; a carrier bar control mechanism including carrier nuts and a ratcheting device to actuate the same; a narrowing mechanism including narrowing rods and narrowing combs operable to transfer certain loops in certain of said courses for fashioning the fabric; a narrowing rod motion mechanism including narrowing nuts and a ratcheting device to actuate the same; a lace attachment including a loop transfer device movable to operating position in relation to said needle bar to transfer thereon all the loops in certain of said courses for forming lace designs in the fabric; and means controlled by said transfer device and operable, upon movement of the latter to operating position, for automatically setting the lace attachment for actuation and including elements adapted to disrupt the function of said ratcheting devices for preventing the action of the carrier bar control mechanism and the narrowing rod motion mechanism simultaneously with the setting of the lace attachment for actuation.

10. In a flat knitting machine having a loop transfer device movable longitudinally of the machine, an attachment for imparting longitudinal movements to said device over different distances, comprising: a pattern control sectional member consisting of telescoping sections and engageable with said device to transmit longitudinal movements thereto; and pattern control means operable to relatively adjust the telescoping sections of said member for prepositioning said device.

11. In a flat knitting machine having a loop transfer device movable longitudinally of the machine, an attachment for imparting longitudinal movements to said device over different distances, comprising: pattern means; a slideable sectional member consisting of telescoping sections, one section engageable with said pattern means and the other section engageable with said device whereby said member may transmit longitudinal movements to said device from said pattern means; and pattern control means operable to relatively adjust the telescoping sections of said member for prepositioning said device with respect to said pattern means.

12. In a flat knitting machine having a loop transfer device movable longitudinally of the machine, an attachment for imparting longitudinal movements to said device over different distances, comprising: pattern means; a slideable sectional member consisting of telescoping sections, one section engageable with said pattern means and the other section engageable with said device whereby said member may transmit longitudinal movements to said device from said pattern means; and means controlled by said pattern means and operable to relatively adjust the telescoping sections of said member for prepositioning said device with respect to said pattern means.

13. In a flat knitting machine having a loop transfer device movable longitudinally of the ma-

chine, an attachment for imparting longitudinal movements to said device over different distances, comprising: pattern means including two sets of pattern elements; a slideable sectional member

5 consisting of telescoping sections, one section engageable with one set of pattern elements of said pattern means, and the other section engageable with said device whereby said member may transmit longitudinal movements to said device from said pattern means; and means controlled by the other set of said pattern elements of said pattern means and operable to relatively adjust the telescoping sections of said member for prepositioning said device with respect to said pattern means.

14. In a flat knitting machine having a bank of needles and a loop transfer device provided with loop engaging instrumentalities operable to remove the loops off certain needles and thereafter to return said loops onto certain other needles: an attachment comprising a pattern member; adjustable means controlled by said pattern member and acting on said loop transfer device to displace its loop engaging instrumentalities from positions related to said certain needles to positions related to said certain other needles intermediately of the loop removing and returning operations of said instrumentalities; and means also controlled by said pattern member to adjust said adjustable means for action on said device to locate the loop engaging instrumentalities thereof with respect to the needles prior to the actuation of said device for the loop removing operations of said loop engaging instrumentalities.

20 15. In a flat knitting machine having a bank of needles and a loop transfer device provided with loop engaging instrumentalities operable to remove the loops off certain needles and thereafter to return said loops onto certain other needles: an attachment comprising a pattern member and acting on said loop transfer device to displace its loop engaging instrumentalities from positions related to said certain needles to positions related to said certain other needles intermediately of the loop removing and returning operations of said instrumentalities; and means also controlled by said pattern member to adjust said adjustable means for action on said device to locate the loop engaging instrumentalities thereof with respect to the needles prior to the actuation of said device for the loop removing operations of said loop engaging instrumentalities.

25 16. In a flat knitting machine having a bank of needles and a loop transfer device provided with loop engaging instrumentalities operable to remove the loops off certain needles and thereafter to return said loops onto certain other needles: an attachment comprising a pattern member including two sets of pattern elements; adjustable means controlled by one set of pattern elements of said pattern member and acting on said loop transfer device to displace its loop engaging instrumentalities from positions related to said certain needles to positions related to said certain other needles intermediately of the loop removing and returning operations of said instrumentalities; and means controlled by the other set of pattern elements of said pattern member to adjust said adjustable means for action on said device to locate the loop engaging instrumentalities thereof with respect to the needles prior to the actuation of said device for the loop removing operations of said loop engaging instrumentalities.

30 17. In a flat knitting machine having a bank of needles and a loop transfer device provided with loop engaging instrumentalities operable to remove the loops off certain needles and thereafter to return said loops onto certain other needles: an attachment comprising a rotatable pattern wheel including two sets of pattern elements; adjustable means controlled by one set of pattern elements of said pattern wheel and acting on said loop transfer device to displace its loop engaging instrumentalities from positions related to said certain needles to positions related to said certain other needles intermediately of the loop removing and returning operations of said instrumentalities; and means controlled by the other set of pattern elements of said pattern wheel to adjust said adjustable means for action on said device to locate the loop

engaging instrumentalities thereof with respect to the needles prior to the actuation of said device for the loop removing operations of said loop engaging instrumentalities.

17. In a flat knitting machine having a main cam shaft, a bank of needles, and a loop transfer device provided with loop engaging instrumentalities operable to remove the loops off certain needles and thereafter return said loops onto certain other needles: an attachment comprising a rotatable pattern member; a cam on the main cam shaft; means arranged between said cam and pattern member to impart intermittent rotation to the latter; adjustable means controlled by said pattern member and acting on said loop transfer device to displace its loop engaging instrumentalities from positions related to certain needles to positions related to said certain other needles intermediately of the loop removing and returning operations of said instrumentalities; and means also controlled by said pattern member to adjust said adjustable means for action on said device to locate the loop engaging instrumentalities thereof with respect to the needles prior to the actuation of said device for the loop removing operations of said loop engaging instrumentalities.

18. In a flat knitting machine having a main cam shaft, a bank of needles and a loop transfer device provided with loop engaging instrumentalities operable to remove the loops off certain needles and thereafter return said loops onto certain other needles: an attachment comprising a rotatable pattern wheel including two sets of pattern elements; a cam on the main cam shaft; means arranged between said cam and pattern wheel to impart intermittent rotation to the latter; adjustable means controlled by said pattern wheel and acting on said loop transfer device to displace its loop engaging instrumentalities from positions related to certain needles to positions related to certain other needles intermediately of the loop removing and returning operations of said instrumentalities; and means also controlled by said pattern wheel to adjust said adjustable means for action on said device to locate the loop engaging instrumentalities thereof with respect to the needles prior to the actuation of said device for the loop removing operations of said loop engaging instrumentalities.

19. In a flat knitting machine, the combination with the picot rod thereof operable to remove the loops off certain needles and thereafter to return said loops onto certain other of the needles: of an attachment comprising a pattern member; adjustable means controlled by said pattern member and acting on said picot rod to displace the same intermediately of the loop removing and returning operations thereof; and means also controlled by said pattern member to adjust said adjustable means for action on the picot rod to locate the same with respect to the needles prior to the actuation of said picot rod in its loop removing operation.

20. In a flat knitting machine, the combination with the picot rod thereof operable to remove the loops off certain needles and thereafter to return said loops onto certain other needles; an attachment comprising a pattern member including two sets of pattern elements; adjustable means controlled by one set of pattern elements of said pattern member and acting on said picot rod to displace the same intermediately of the loop removing and returning oper-

ations thereof; and means controlled by the other set of pattern elements of said pattern member to adjust said adjustable means for action on the picot rod to locate the same with respect to the needles prior to the actuation of said picot rod in its loop removing operations.

21. In a flat knitting machine, the combination with the picot rod thereof operable to remove the loops off certain needles and thereafter to return said loops onto certain other needles: an attachment comprising a rotatable pattern wheel including two sets of pattern elements; adjustable means controlled by one set of pattern elements of said pattern wheel and acting on said picot rod to displace the same intermediately of the loop removing and returning operations thereof; and means controlled by the other set of pattern elements of said pattern wheel to adjust said adjustable means for action on the picot rod to locate the same with respect to the needles prior to the actuation of said picot rod in its loop removing operations.

22. In a flat knitting machine, the combination with the main cam shaft, and the picot rod thereof operable to remove the loops off certain needles and thereafter to return said loops onto certain other needles: an attachment comprising a rotatable pattern member; a cam on the main cam shaft; means arranged between said cam and pattern member to impart intermittent rotation to the latter; adjustable means controlled by said pattern member and acting on said picot rod to displace the same intermediately of the loop removing and returning operations thereof; and means also controlled by said pattern member to adjust said adjustable means for action on the picot rod to locate the same with respect to the needles prior to the actuation of said picot rod in its loop removing operation.

23. In a flat knitting machine, the combination with the main cam shaft, and the picot rod thereof operable to remove the loops off certain needles and thereafter to return said loops onto certain other needles: an attachment comprising a rotatable pattern wheel including two sets of pattern elements; a cam on the main cam shaft; means arranged between said cam and pattern wheel to impart intermittent rotation to the latter; adjustable means controlled by said pattern wheel and acting on said picot rod to displace the same intermediately of the loop removing and returning operations thereof; and means also controlled by said pattern member to adjust said adjustable means for action on the picot rod to locate the same with respect to the needles prior to the actuation of said picot rod in its loop removing operation.

24. In a flat knitting machine, the combination with a bank of needles of a mechanism including loop engaging instrumentalities; a sectional member operable to impart sliding movement to said instrumentalities longitudinally of the bank of needles; a slideable wedge interposed between the sections of said member and acting thereon to cause the placement of said instrumentalities in a definite relation with respect to the needles; rotating cam means; and a pivotal member engaging said cam means and connected to said slideable wedge to translate the rotating movement of the former into the sliding movement of the latter.

25. In a flat knitting machine having a loop transfer device movable longitudinally of the machine, an attachment for imparting longitudinal movements to said device over different

distances comprising: a pattern control sectional member consisting of telescoping sections and engageable with said device to transmit longitudinal movements thereto; and a pattern control element associated with the telescoping sections and having a stepped surface operable to relatively adjust the telescoping sections of said member for prepositioning said device.

26. In a flat knitting machine having a loop transfer device movable longitudinally of the machine, an attachment for imparting longitudinal movements to said device over different

distances comprising: a pattern control sectional member consisting of telescoping sections and engageable with said device to transmit longitudinal movement thereto; an element having a series of stepped surfaces associated with the telescoping sections to adjust the same relatively to each other; and cam means operatively connected to said element for the operation thereof to bring the various stepped surfaces thereof into operative relation with the telescoping sections.

FRITZ LAMBACH.
